CONTAINER MANUFACTURE

Walter E. Sooy and Rudolf William von Sydow,
Middletown, Ohio, assignors, by mesne assignments,
to Continental Can Company, Inc., New York, N. Y., a corporation of New York

Application December 18, 1939, Serial No. 309,796

15 Claims. (Cl. 93—81)

This invention relates to the formation of tubular bodies for containers and the like from fibrous material.

It is a principal object of the invention to provide a simple and effective process for forming easily and rapidly a laminated wound tubular body having an inner surfacing liner substantially confined to the exposed inner surface and of a character effectively impervious to the passage of the contents of the container and having an outer ply adapted to provide additional strength with the plies being united and wound to produce a relatively smooth surface upon which an end member may be secured in sealed relation.

It is a further object to provide such a process in which the outer or main body ply is wound from a web in the same direction as that in which it was formed so that the grain of the web runs in the direction of the periphery of the wound tubular body.

It is a still further object to provide a simple and effective apparatus for carrying out the above objects.

It is also an object to provide a tubular container body having substantial strength and stiffness and formed with a main body web convolutely wound in the direction of its formation with two or more plies and having an inner web secured to the main body web and extending over and substantially limited to the exposed interior of the formed container body to provide an effectively impervious interior surfacing thereon.

Other objects and advantages will be apparent from the following description, the accompanying drawing, and the appended claims.

In the drawing—

Fig. 1 is a schematic view showing apparatus for practicing the present invention;

Fig. 2 is a detail elevational view of a portion of the drive mechanism which provides for intermittent and timed operation of the feed rolls; and

Fig. 3 is a partial sectional view on an enlarged scale through the wall of a container body formed in accordance with the present invention.

This invention has particular application to the formation of tubular bodies for containers and the like from a jumbo roll of paper by suitably cutting the paper into lengths and winding such lengths into the form of convolute container bodies. This is preferably accomplished on a machine having a rotating mandrel assembly in which individually rotatable mandrels are successively carried through a series of forming posi-

tions in which the several forming operations are carried out. A machine of this character is that shown in the Scusa et al. Patent No. 2,163,318 of June 20, 1939, assigned to the same assignee as this application, which will be referred to throughout the present case for purposes of illustration.

In accordance with the invention means are provided for forming a product consisting of a main body web with a liner web of shorter length, and united with the main web in predetermined relation so that upon being wound into container form, the liner web completely overlies the main body web and forms the inner surfacing for the container. This liner is preferably formed of material of different character from the main web, and such as to afford adequate resistance to the penetration of the contents of the container. As an example of material which may be satisfactorily utilized, the main body web may consist of the usual paperboard of suitable thickness, color, strength and other characteristics, with the liner consisting of a superior sheet selected to have resistance to the penetration of solvents, water, moisture, oils, grease, etc., and comprising for example a sheet of parchment paper or other material having the protective interior surfacing characteristics desired. Both such materials may be supplied in the form of jumbo rolls, and webs fed therefrom in a continuously forward manner and wound in the same direction. Under such circumstances the sheet is wound in the same direction in which its initial formation took place and hence the grain of the sheet runs in the direction of the periphery of the formed container. This is particularly advantageous in the case of the main body web, since it provides for increased strength and stiffness in the final product as contrasted with a container in which the grain of the sheet runs parallel with the axis of the container.

The forming operation may be carried out in different ways and preferably by the use of timed feeding cut-off means coordinated with the winding operation to provide for the bringing together of the body web and the liner web in predetermined relation to each other so that when wound the liner web will occupy the desired location upon the interior of the container and provide for developing the desired protective action upon the inner surface.

Reference is accordingly made to the accompanying drawing which shows schematically a preferred embodiment of the invention and in which the jumbo roll of paper or paper material

for forming the main body web is indicated partially at 10. This web is unwound from the roll, passing under guide roll 11, and through a pair of feed rolls 12 which provide for feeding the web forwardly and are suitably controlled to provide for an intermittent feeding action of proper duration with periods of stoppage between successive feeding operations. The drive for such feed rolls has not been illustrated in detail, as it is shown fully in the above referred to Scusa et al. patent; in general however it provides for controlled operation of the feed rolls in the above described manner for the purpose of intermittently feeding a predetermined desired length of web material from the jumbo roll. This length is such as to provide the desired number of plies for the main web when wound into ultimate container form, preferably such that the wound container consists of three complete overlying plies of the body web with an additional portion of a ply such as to offset the outer seam from the inner seam.

In front of the feed rolls 12 there is located a cut-off knife 15 which operates with a shearing action across the entire width of the web to sever the same into lengths. In order to provide for the timed operation of the cut-off knife during periods of stoppage of feeding, the drive therefore is coordinated with the drive for the remainder of the machine, and comprises a sprocket wheel 16 which is driven in correlated relation to the main drive mechanism of the machine, such mechanism not being shown in detail. Sprocket wheel 16 is fastened to a cross shaft 17 suitably journaled in the main side frames 18 of the machine and the drive of sprocket wheel 16 is so arranged that shaft 17 makes a complete revolution once during each cycle of operation of the machine. Fastened to shaft 17 is a cam member 20 having a cam track 21 formed upon the face thereof of such contour as to provide for maintaining the knife in raised position during the greater portion of the cycle, and to cause a drop of the knife and a corresponding shearing action at a predetermined point in the cycle. This is accomplished by means of a cam follower 22 traveling in the track 21 which actuates one arm 23 of a bell crank lever pivotally supported at 24. The other arm 25 of the lever carries a pin 26 adapted to yieldingly engage a socket 26a formed in lever 27 which is loosely mounted upon shaft 24 so that in the event of abnormal resistance being encountered, the pin 26 will be withdrawn from its driving engagement with lever 21, without damage to the mechanism.

Fastened to lever 27 is a connecting rod 28 which is suitably connected as shown at 29 to the upper element of the shearing knife 15. This arrangement is such that upon rotation of cam 20, cam follower 22 will be actuated during the major portion of the rotation of the cam in such position as to raise connecting rod 28 to its upper position, where the shearing knife is held out of shearing engagement with the web, to provide for the feeding of the web therethrough. At a proper point in the cycle, corresponding to the period of stoppage of the feed rolls 12, the connecting rod 28 is actuated downwardly to thereby cause the shearing of the web of paper. The shearing knife is promptly withdrawn from shearing position prior to the beginning of a subsequent cycle of feeding operation.

The sheared length of paper 30 which is to form the main body web of the tubular container as shown in Fig. 1 is engaged adjacent its forward part by pairs of feed rolls 31 and 32. Thus

upon initiation of the subsequent feeding cycle, these positively driven feed rolls provide for carrying the web forward, and suitable drive connections are provided for such feed rolls from the main drive of the machine in the manner described in the Scusa et al. patent to secure the operation thereof in coordinated relation to the operation of the remaining parts of the machine.

If desired the web 30 may be passed through a series of spaced slitter members 34 located at intervals across the width of the web to cause the slitting thereof into a plurality of individual strips adapted to form separate container bodies; or if desired this slitting mechanism may be eliminated and a single web supplied for the formation of only a single elongated container body.

Passing through feed rolls 36, the web is then brought into receiving relation with the grippers 37 carried by a forming mandrel 38. This mandrel is preferably mounted in a mandrel assembly indicated generally at 39 comprising a plurality of similar forming mandrels adapted to be progressively rotated through a series of forming positions in which the several forming operations incident to the winding of the web into tubular body form take place. In order to retain the web in wound form, means are provided for adhesively securing the wound body, including a reservoir 40 containing a suitable adhesive material in which there rotates an adhesive pick-up roll 41 which supplies adhesive to a transfer roll 42. Such transfer roll 42 is preferably mounted for oscillatory movement and is controlled in relation to the forming operation of the machine so that as the web is brought around on the surface of mandrel 38, the transfer roll 42 may be brought into adhesive transferring relation with the web, to transfer adhesive to such portion thereof as desired. Usually adhesive is desired to be applied to the leading edge and throughout the remainder of the body of the web to adhesively secure the same in wound condition and to provide an outer surface carrying adhesive and suitable for securing a label thereon. While this adhesive application may be effected upon the web itself prior to its being wound it is preferred to carry out such operation while the web is being wound upon the mandrel substantially as shown.

Following the forming operations with or without the application of a label, the mandrel with the formed tubes thereon is brought into the final or stripping position, in which the formed body or bodies are removed therefrom for further use.

In order to provide the desired surfacing or liner ply having the desired resistance to penetration of the contents of the container, and to locate the same upon the interior surface of the tubular body in conjunction with the forming operations for the main body part itself, a roll of such surfacing material is indicated at 50 comprising for example a roll of parchment paper or other fibrous or sheet material of approximately the same width as the main body web and adapted to produce the desired surface characteristics upon the interior of the container. A web 51 of this material passes over an idler roll 52 and through a feed roll pair 53 which provide for the forward feeding of the web in controlled and correlated relation to the operation of the machine in a manner to be described more in detail. The sheet passes a cut-off knife mechanism indicated at 54, and into contact with an adhesive application roll 55 which is supplied with adhesive by a

pick-up roll 56 dipping within a reservoir 57 containing a suitable adhesive. This application of adhesive may if desired be made across the entire width of the web 51 by utilizing a transfer roll 55 having a uniform cylindrical surface; or the adhesive may be located in transversely spaced strips by means of a transfer roll 55 having grooves thereon to provide for applying separated continuous bands of adhesive to the web where such reduced adhesive application will serve adequately to retain the webs in proper laminated relationship to each other.

The adhesively coated web then passes under one or more guide rolls 58 which may be formed to engage and guide the web of paper in those areas between the adhesive applications. The web 51 is then brought into the nip of the feed rolls 31 where it meets the main body web 30, and is effectively united therewith under the pressure of the feed rolls to secure a properly laminated product.

It is important to provide for the proper correlated action of the means for cutting and feeding the liner web in relation to the main body web and to provide for feeding the proper length of such web, at a proper rate of feed, and in proper timed relation to the feeding of the main web. This is preferably effected by means of a drive from the shaft 17 to assure the definite correlation with the operation of the remainder of the machine. For this purpose the shaft 17 which rotates continually at a speed corresponding to one revolution per cycle of operation is provided on its outer end with a disk 60 suitably keyed to rotate with the shaft and carrying a crank pin 61 thereon. A pitman 62 driven by the crank pin provides for the driving of a ratchet lever 63 which is mounted for free swinging movement upon a stud 64 carried by means of an upwardly extending bracket 65 fastened to the main frame member 18. Ratchet lever 63 is thus adapted to pivot upon stud 64 in response to the rotation of disk 60, and at its opposite end carries a pivotally mounted dog 66 which is adapted to engage in driving relation with a toothed ratchet wheel 67. Ratchet wheel 67 is fastened to a shaft 68 suitably journaled in the main frame member 18, and upon its inner face and fastened thereto for rotation therewith is a driving sprocket wheel 70. A sprocket chain 71 passes over the sprocket wheel 70 and over a sprocket wheel 72 fastened to and rotatable with one of the rolls of the feed roll pair 53. Suitable drive means may be provided as desired for positively actuating the other roll of the pair to provide for simultaneous driving operation for both of the rolls.

With this driving arrangement it will be apparent that a definite rotary movement is imparted to the feed rolls 53 once during each cycle of operation of the machine, and at a predetermined point in such cycle. The degree of such rotary movement may be varied by changing the extent of driving engagement which takes place between the dog 66 and the ratchet teeth 67 by means of an adjustable cover slide 73 which may be varied to expose more or less of the ratchet wheel for driving engagement with the ratchet. Likewise the point in the cycle at which the driving operation commences may be varied by shifting the relation of the disk 60 or the crank pin 61 thereon with respect to its drive shaft 17.

These parts are preferably so adjusted that as the main web 30 advances toward the feed roll pair 31, the liner web 51 is also advanced for-

wardly, the feed thereof being initiated at a proper time so that the leading edge of web 51 will meet or if desired precede the leading edge of the main web 30 by a small amount. It is usually found desirable to provide this short leading projection, indicated at 75, of the inner web in relation to the main web. The purpose of such leading edge strip is to provide a portion adapted to overlap upon the trailing end of the inner web 51, as shown in Fig. 3, making it unnecessary to secure complete precision in the length of the webs, while at the same time assuring the establishment of a completely effective interior surfacing of the inner web material. As clearly indicated in Fig. 3, this leading edge portion 75 is adapted to overlap and contact the trailing end of the web 51 to thus provide a limited area of overlap upon itself which is adequate to take care of any variations in the length of the webs and to assure the presence of a complete surfacing of this liner web material upon the interior of the formed body.

With the two webs in the position shown in Fig. 1, the feeding action of both webs has stopped, and the severing of the main web is taking place under the action of the shearing means 15. It is desired to simultaneously sever the inner web 51, and for this purpose the connecting rod 28 is provided with an arm 80 having an elongated slot 81 therein within which there is slidably located a pin 82 carried by one arm 83 of a bell crank lever pivotally mounted at 84. The other arm 85 of the lever is fastened to a connecting rod 86 which is caused to move at right angles to the direction of movement of the main connecting rod 28. The rod 86 is suitably attached to the movable portion of the shearing knife 54 by means of link 87, so that upon downward movement of connecting rod 28 with its resultant shearing action with respect to the main web, a transverse movement of knife means 54 with a similar shearing action is effected with respect to the liner web 51.

This shearing knife 54 is located at a proper distance from the leading edge of the sheared length of inner web to provide sufficient length of material therein to overlie the entire inner surface of the container body and to form the overlapping portion 75 as desired.

Upon the shearing operations as above described taking place, and the subsequent forward feeding of both webs under the action of the driven feed rolls 31 and 32, the trailing part of the severed web 51 will be drawn forwardly past the adhesive applying roll 55 and into adhering contact with the main web 30 to form the desired laminated sheet. Feeding of a subsequent length of the main web material is initiated promptly with the beginning of the subsequent cycle of operation. A similar feed of the liner web does not immediately take place, because a shorter length of such web material is desired, for example about one-third the length of the main web. Accordingly initiation of such feeding is delayed until, under the action of the intermittent drive for the feed rolls 53 as previously described, the proper time in the cycle is reached to begin the feed and to provide the web 51 in proper meeting relation with respect to the main web 30.

If desired the adhesive pick-up roll 56 may be positively driven in a continuous manner and application rolls 55 and guide rolls 58 allowed to rotate by frictional contact with the web so that they will perform their desired operations during

the passage of the web thereover, and at other times will not rotate unnecessarily. Any excess adhesive supplied by roll 56 during periods of stoppage of roll 55 merely flows back into reservoir 57 and the desired amount of adhesive on roll 55 is maintained thereon by passage through the nip of rolls 55, 56. Likewise the adhesive for laminating the webs may be applied to the main web over that portion which is covered by the liner web.

The winding operations as effected upon the laminated web are preferably carried out in the same manner as with a single sheet, the leading edge 75 being engaged under the grippers, and adhesive to retain the wound plies in place being provided by adhesive roll 42 as previously described. In its wound form the web has substantially the construction as shown in Fig. 3 with its entire interior effectively covered and rendered impervious to the passage of the contents of the container. It will also be noted that the short overlapped portion of the liner sheet is located in predetermined relation with respect to the inner end or seam of the main body web that it is immediately adjacent and substantially abutting the inner edge of such main web. This facilitates smooth winding and there is no sharp change in cross-sectional thickness at any portion of the tubular body, even at the zone where the main and liner webs terminate, and the preferred construction is such that variations in thickness are reduced to substantially a single thickness of material and such variation is not so sharp or abrupt but that the end member may be properly secured and sealed in place. The body web is usually of greater thickness than the liner web and in the present construction the maximum change or difference in thickness is not in excess of one thickness of the body web itself. This is advantageous in the later application of an end member, such as a metal end cap which is crimped over the ends of the body wall and which may be secured in effectively sealed relation thereon without the occurrence of leakage or seepage such as is apt to occur with a tubular body in which there is abrupt change in section. Also as will be clear from the foregoing, the feeding and winding of both webs proceeds at all times in the same forward direction providing for smooth uninterrupted operation and resulting in production of the desired convoluted wound bodies with the grain of the web running in the general direction of the periphery thereof.

While the process, apparatus, and article herein described constitute preferred embodiments of the invention, it is to be understood that the invention is not limited to this precise process, apparatus, and article, and that changes may be made therein without departing from the scope of the invention which is defined in the appended claims.

What is claimed is:

1. Apparatus of the character described for producing multi-wall convoluted wound container bodies or the like comprising means for feeding forward a main web for a distance equal to the blank length of a container body portion, means for feeding toward said main web a liner web of a length substantially equal to the perimeter of the formed container, means for applying adhesive to be effective only in the overlapping portions of said main web and said liner web to unite said webs together, and means

for feeding said liner web into registering position with the portion of said main web which forms the container interior to be adhesively secured thereto to provide a protective lining upon the interior of the formed container.

2. Apparatus of the character described for producing multi-wall convoluted wound container bodies or the like comprising means for intermittently feeding forward a main web from a jumbo roll for a distance equal to the blank length of a container body portion, means for intermittently feeding a liner web of material adapted to provide a protective interior surfacing from a supply roll for a distance substantially equal to the perimeter of the formed container, means operable during periods of stoppage of both webs for severing the fed portions of both said webs, means for applying adhesive to be effective to unite said main web and said liner web, and means for feeding said liner web portions into predetermined relation with the portions of said main web which form the container interiors to be adhesively secured thereto to provide a protective lining upon the interior of the formed container bodies.

3. Apparatus of the character described for producing multi-wall convoluted wound container bodies or the like comprising means for intermittently feeding forward a main web from a jumbo roll for a distance equal to the blank length of a container body portion, means for intermittently feeding a liner web of material adapted to provide a protective interior surfacing from a supply roll for a distance substantially equal to the perimeter of the formed container, means operable during periods of stoppage of both webs for severing the fed portions of both said webs, means for applying adhesive to be effective to unite said main web and said liner web, and means for feeding said liner web portions into predetermined relation with the portions of said main web which form the container interiors to be adhesively secured thereto, and means for thereafter winding said composite webs with said liner web innermost to provide a protective lining upon the interior of the formed container bodies.

4. Apparatus of the character described for forming a convolute wound container body which comprises means for feeding a main body web of paper material, means for cutting off a length of said main body web sufficient to form two or more plies of the wound body, means for feeding a liner web of substantially the same width as the main web and having protective characteristics for the interior surface of the body, means for cutting off a shorter length of the liner web sufficient to form an inner protective lining upon the wound container body, means for applying the liner web in overlying relation to one surface of said main web, and means for winding the separated lengths in the direction of the grain of said material and with the liner web innermost and completely overlying the inner surface thereof.

5. Apparatus of the character described for forming a convolute wound container body which comprises means for intermittently feeding a main body web, means for cutting off a length of said main body web sufficient to form two or more plies of the wound body, means for intermittently feeding a liner web of substantially the same width as the main web, means for cutting off a shorter length of the liner web sufficient to

form an inner protective lining upon the wound container body, means for operating both said cutting means simultaneously and during periods of stoppage of feed of said webs, means for applying the liner web in overlying relation to one surface of said main web, and means for winding the separated lengths with the liner web innermost and completely overlying the inner surface thereof.

6. Apparatus of the character described for forming a convolute wound container body which comprises means for feeding a main body web, means for cutting off a length of said main body web sufficient to form two or more plies of the wound body, means for feeding a liner web of substantially the same width as the main web into contact with the main web and with the leading edge thereof projecting forwardly beyond said main web a limited distance, means for cutting off a shorter length of the liner web sufficient to form an inner protective lining upon the wound container body, and means for winding the body with the liner web innermost and completely overlying the inner surface thereof and with said projecting edge overlapping upon itself.

7. Apparatus of the character described for forming a convolute wound container body which comprises means for intermittently feeding a main body web, means for cutting off a length of said main body web sufficient to form two or more plies of the wound body, means for intermittently feeding a liner web of substantially the same width as the main web into contact with the main web and with the leading edge thereof projecting forwardly beyond said main web a limited distance, means for cutting off a shorter length of the liner web sufficient to form an inner protective lining upon the wound container body, means for operating both said cutting means simultaneously and during periods of stoppage of feed of said webs, and means for winding the body with the liner web innermost and completely overlying the inner surface thereof.

8. The method of forming multi-wall convolutely wound container bodies which comprises the steps of feeding forward a main web of a length sufficient to form two or more plies, feeding a liner web having a protective surfacing of substantially the same width as the main web and of a length shorter than said main web and substantially equal to the perimeter of the formed container plus a short overlap, applying adhesive limited to be effective between the contacting faces of said main web and said liner web to unite said webs, and winding said webs with said liner web into predetermined position with relation to the portion of said main web which forms the container interior to be adhesively secured thereto to provide a protective lining upon the interior of the formed container and with the overlapped portion being located adjacent and substantially abutting the inner edge of the main body web.

9. The method of forming a multi-wall convolute wound container body which comprises the steps of intermittently feeding forward a main web for a distance corresponding to the blank length of a container body portion, intermittently feeding toward said main web a liner web of a length substantially equal to the perimeter of the formed container, cutting said webs concurrently during periods of stoppage of feed thereof, applying adhesive to be effective to unite said main web and said liner web, and feeding said liner web and said main web into predeter-

mined overlying relation with the liner web located upon the portion of the main web which forms the interior of the container to be adhesively secured thereon and to provide an impervious interior surfacing upon a formed container.

10. The method of forming a convolute wound container body of the character described which comprises feeding a main body web of paper material, cutting off a length thereof sufficient to form two or more plies of the wound body, feeding a liner web of substantially the same width as the main web and adapted to provide a protective interior surfacing on the wound container body, cutting off a shorter length of the liner web sufficient to form an inner protective lining upon the wound container, applying the liner web in overlying relation to one surface of said main web, and winding the separated lengths in the direction of the grain of said material and with the liner web innermost and completely overlying the inner surface thereof.

11. The method of forming a convolute wound container body of the character described which comprises intermittently feeding a main body web, cutting off a length thereof sufficient to form two or more plies of the wound body, intermittently feeding a liner web of substantially the same width as the main web, cutting off a shorter length of the liner web sufficient to form an inner protective lining upon the wound container, performing said cutting operations simultaneously during periods of stoppage of feeding of said webs, applying the liner web in overlying relation to one surface of said main web, and winding the separated lengths with the liner web innermost and completely overlying the inner surface thereof.

12. The method of forming a convolute wound container body of the character described which comprises feeding a main body web, cutting off a length thereof sufficient to form two or more plies of the wound body, feeding a liner web into contact with the main web cutting off a shorter length of the liner web sufficient to form an inner protective lining upon the wound container and a short overlap, and winding the body with the liner web innermost in predetermined relation and completely overlying the inner surface thereof and lapped upon itself with the overlapped portion of the liner web being located immediately adjacent and substantially abutting the inner edge of said main web.

13. The method of forming a convolute wound container body of the character described which comprises feeding a main body web, cutting off a length thereof sufficient to form two or more plies of the wound body, feeding a liner web into contact with the main web and with the leading edge thereof projecting forwardly beyond said main web a limited distance, cutting off a shorter length of the liner web sufficient to form an inner protective lining upon the wound container, and winding the body with the liner web innermost and completely overlying the inner surface thereof.

14. Apparatus of the character described for forming a multi-wall convolute wound container body which comprises means for feeding a main body web of a length sufficient to form two or more plies, means for feeding a thin liner web having characteristics of resistance to grease or moisture and the like and of substantially the same width as the main web and of a length substantially equal to the perimeter of the formed

container plus a short overlap into position for extending a short distance beyond the leading end of the main body web, means for applying adhesive to be effective upon the outer surface of said liner web to retain the body in wound form, and means for winding the body and liner webs with the liner web innermost and completely overlying the inner surface of the body thus formed and overlapping itself flatwise for a limited distance close beside and beyond the inner end of the main body web with the overlapped end edge of the liner web substantially abutting said main body web inner end.

15. The method of forming a multi-wall convolute wound container body which comprises the steps of feeding forward a main web for a distance corresponding to the blank length of a container body portion, feeding toward said main web a liner web of a width substantially equal to that of the main web and of a thickness no

greater than half the thickness of the main web and of a length substantially equal to the perimeter of the formed container plus a slight overlap, applying adhesive limited to be effective between the contacting faces of said main web and said liner web to unite said webs, and winding said webs with said liner web and said main web in predetermined overlying relation with the liner web located upon and extending slightly beyond the portion of the main web which forms the interior of the container to be adhesively secured thereon and to provide an impervious interior surfacing upon the formed container and with the liner web ends overlapping beside and beyond the inner end of the main web whereby the maximum variation in thickness of said wound body will not exceed the thickness of a single ply of said main web.
